CLAIM

We claim the ornamental design for a clip, as shown and described.

DESCRIPTION

FIG. 1 is a front view of a clip shown in the closed position in accordance with our new design;

FIG. 2 is a rear view thereof;

FIG. 3 is a top elevation view thereof;

FIG. 4 is a bottom elevation view thereof;

FIG. 5 is a side elevation view thereof;

FIG. 6 is a side elevation view thereof, for the side opposite that of FIG. 5;

FIG. 7 is an isometric view thereof;

FIG. 8 is a front view of a clip shown in the open position in accordance with our new design;

FIG. 9 is a rear elevation view thereof;

FIG. 10 is a top elevation view thereof;

FIG. 11 is a bottom elevation view thereof;

FIG. 12 is a side elevation view thereof;

FIG. 13 is a side elevation view thereof, for the side opposite that of FIG. 13; and,

FIG. 14 is an isometric view thereof.

The broken lines depict portions of the article that form no part of the claimed design.
